DESIGN FOR A COMBINED HANDLE AND HOLDER FOR SAFETY RAZORS AND THE LIKE

Jacques Martial Bars and Robert C. Skulnick,
New York, N. Y.

Application February 19, 1940, Serial No. 90,358

Term of patent 7 years

To all whom it may concern:

Be it known that Jacques Martial Bars and Robert C. Skulnick, citizens of the United States and residents of New York city, in the county of New York and State of New York, have invented a new, original, and ornamental Design for Combined Handle and Holder for Safety Razors and the like, of which the following is a specification, reference being had to the accompanying drawing forming part thereof, in which:

Figure 4 is a perspective view of the device when opened; and

We claim:

The ornamental design for a combined handle and holder for safety razors and the like, substantially as shown.
